UNITED STATES PATENT OFFICE.

HARRY C. RICKENBACH AND GEORGE E. ROESCH, OF PITTSBURGH, PENNSYLVANIA.

INTERCHANGEABLE-STEEL-TYPE HOLDER.

Application filed June 6, 1923. Serial No. 643,653.

To all whom it may concern:

Be it known that we, HARRY C. RICKENBACH and GEORGE E. ROESCH, citizens of the United States, residing at Pittsburgh, in the county of Allegheny and State of Pennsylvania, have invented certain new and useful Improvements in Interchangeable-Steel-Type Holders, of which the following is a specification:

10 The present invention consists of an interchangeable steel type holder especially adapted for use in stamping billets in steel mills.

An object of the invention is to provide 15 a type holder which positively and effectively holds the type from displacement notwithstanding the complete elimination of springs and all other elastic tension means, yet permitting the type to be expeditiously 20 expelled from the holder without grasping the latter.

A co-ordinate object of the invention is to provide a durable holder of simple construction which embraces the type in such 25 a manner that the application of force to the holder causes the type to be more firmly gripped and transmits the impact of the applied force directly to the holder thereby relieving the less durable parts of the holder 30 from strain.

A further object of the invention is to provide a type holder which embodies a movable element mounted in the holder body in such a manner that the type is supported 35 directly thereon, is clamped by the movable part and expelled by the movement of the latter.

Additional objects of the invention will be apparent from the following description 40 of the present preferred form of the invention taken in connection with the accompanying drawings, wherein:—

Fig. 1 is a longitudinal sectional view of a holder constructed in accordance with this 45 invention illustrating its application;

Fig. 2 is a side elevational view of the holder; and

Fig. 3 is a top plan view of the same.

The holder of the present invention consists of a body portion preferably made of metal and of any desired configuration although in the present instance the butt or impact end 4 thereof is substantially cylindrical while the opposite end 5 is preferably 50 of oblong cross sectional configuration. A portion of one face of the end 5 is removed 55

to provide a recess 6 in which an element generally designated 7 is hinged. The element 7 in the present instance constitutes a movable jaw which co-acts with a portion 8 of the upper end of the holder body said portion 8 capacitating as a fixed jaw. A portion of the inner wall of the element 7, approximately midway the ends of the latter, is extended inwardly to provide a 60 supporting ledge 8' the upper face of which is flat for engagement with type or die characters 9. The bottom face of the ledge is slightly rounded to facilitate movement of the latter across the wall 10 which latter 65 comprises the bottom of the recess 6. The wall 10 is intersected by an elongated recess 11 which communicates with the recess 6 and is relatively narrower than the latter.

Upon reference to Fig. 2 of the drawings, 70 it will be apparent that the upper end of the element or jaw 7 is relatively long so as to complement the recess 6. The lower end of the said jaw issues into a relatively narrow abutment 12 which is movable into the recess 11 on an axis 13. The inner wall of the abutment 12 tapers and is adapted to be impinged by the inner end of a screw shank 14. The shank 14 is shown in the present instance to issue into a handle 15' although 75 it is to be understood that any other type of terminal may be associated with said shank to urge the latter into engagement with or away from the abutment 12.

A rib 15 is formed on the inner face of 80 the fixed jaw 8 and complements corresponding recesses formed in the type or dies 9. Consequently, when the type or dies are deposited in the recesses 6 and are in proper 85 position on the ledge 8', the rib 15 will engage the recesses in the type or dies to prevent casual displacement of the latter.

In use of this holder, the type is deposited 90 in the recess 6 as shown in Fig. 1 of the drawings following which the threaded shank 14 is urged into engagement with the abutment 12 at the lower end of the jaw 7 by rotation of the handle 15'. When the jaw 7 has been urged into the desired contiguity with the type, pressure is applied to 95 the impact end of the holder in a manner well known in the art. When it is desired to release the type the operator may twist the handle as he swings the holder through the arc of a circle thereby retracting the 100 handle 15' and permitting the abutment end 12 of the jaw to recede into the recess 11. 110

This cycle of operation permits the type to move laterally so as to disengage the same from the rib 15 allowing the type to be expelled from the holder by the forward movement of the ledge 8'.

Manifestly, it is unnecessary for the operator to touch the holder which becomes heated when used for stamping hot materials by a hammer or other means. Also, 10 it will be noted that the outer face of the jaw 7 projects appreciably beyond the outer face of the holder body so that the lower end of the jaw may be manually pressed into the recess 11 for expelling the type 15 without the necessity of the hands of the operator coming in contact with the holder.

From the above, it is apparent that the type or dies are positively held in the holder and the application of force to the impact 20 end of the holder causes the type to be more firmly gripped by the jaw 7 in an obvious manner. Notwithstanding this positive and effective gripping of the type the latter can be quickly released and changed. Further-

25 more, when the type or dies are forced inwardly against the ledge 8' under pressure on the impact end of the holder, there will be no strain on the axis 13 of the pivoted jaw 7 since the ledge comes in contact with 30 the wall 10 thereby positively transmitting stress to the body of the holder instead of to the axis or pivot pin 13.

It is to be understood that various changes may be made in this device especially in 35 the details of construction, proportion and arrangement of parts within the scope of the claims hereto appended.

What is claimed is:—

1. An interchangeable steel type holder 40 including a portable steel stamping die holding body provided with a type receiving cavity one of the walls of which is removed, and an element mounted in said body at the point where the wall is removed, said element being equipped with a type receiving ledge and movable to facilitate introduction of the type into and removal of the same from the type receiving cavity of the body.

45 2. A type holder including a body having a recess therein, a jaw pivotally mounted in said recess and provided with a type supporting extension projecting into the latter,

and screw means to urge said jaw into engagement with the type. 55

3. A type holder including a body provided with a type receiving recess, a jaw pivotally mounted in said recess and having an extension thereon to receive the type, said extension being seated on the bottom 60 wall of said recess to prevent strain on the jaw when force is applied to the holder.

4. A type holder of the character described including a holder body, an element movably mounted in said body and adapted 65 to receive said type, means to retain said element in engagement with the type, said element being movable upon release of said means to eject the type.

5. A type holder of the character described including a type holding body, an element pivotally mounted in said body having an extension thereon to support the type, a portion of said element being movable into the body to urge the extension 75 against the type for projecting the latter from the holder.

6. A type holder of the character described including a holder, an element movably mounted in the holder including a type 80 supporting extension, screw means to force the outer end of said element in engagement with the type, said means being releasable to permit the inner end of the element to recede in the holder for urging the extension 85 against the type to eject the latter.

7. An interchangeable steel type holder including a body, a type clamp mounted in said body, and a screw shank one end of which is formed to provide a handle operable to urge the clamp into engagement with the type. 90

8. A steel type holder including a portable steel stamping die holding body, a type supporting and clamping element mounted 95 in said body, the type contacting surfaces of said body and element being flat to snugly embrace the opposite sides and bottom of the type and movable when pressure is exerted on the type to urge the clamping element into more intimate contact with the type. 100

In testimony whereof we affix our signatures.

HARRY C. RICKENBACH.
GEORGE E. ROESCH.
